SHOULDER-STRAP HOLDER

Eugene B. Young, Medford, Mass.

Application May 20, 1935, Serial No. 22,446

2 Claims. (Cl. 24—73)

This invention relates to improvements in shoulder strap holders and it consists in the constructions, arrangements and combinations herein described and claimed.

5 It is an object of the invention to provide a holding device which is of light construction; readily applied to a garment; invisible when applied to a garment, and which will efficiently support a shoulder strap.

10 It is a still further object of the invention to provide a device upon which a shoulder strap may be readily attached or removed therefrom.

Additional objects, advantages and features of invention will be apparent from the following 15 description and accompanying drawing, wherein

Figure 1 is of a garment, a portion thereof being broken away, illustrating my invention in use.

Figure 2 is a fragmentary bottom plan view of 20 the device attached to a garment.

Figure 3 is a view similar to Figure 1, illustrating a modification of the holder.

Figure 4 is a fragmentary top plan view of the 25 garment of Figure 3, with a portion broken away, indicating the relation of the shoulder strap in applied position.

Attention is first directed to Figures 1 and 2 of the drawing, wherein a garment 10 is indicated, generally, and upon the under face of the 30 garment there is secured the shoulder strap 11.

The strap holder 11 is substantially T-shaped in plan, the cross bar 12 extending transversely of the seam 13. The cross bar 12 is provided with a series of apertures 14 around its edge, 35 by means of which the holder is secured to the garment by stitches 15. The cross bar 12 will be positioned adjacent the shoulder of the garment and the free end 16 will therefore be presented toward the neck of the garment.

40 The entire holder may be stamped in a single operation, from any suitable material, such as Celluloid, which will retain its shape, yet will be flexible enough to accommodate itself to the formation of the shoulder without creating an uncomfortable feeling to the wearer.

45 In use, it will only be necessary to slightly flex the free end downwardly slightly from the garment, to permit the strap 11 to be positioned thereover. As soon as the free end 16 assumes its normal position the strap 11 will be borne into frictional contact with the material of the garment, and the pressure and frictional contact will amply support the strap. Any tend-

ency of the strap 11 to slide toward the shoulder is of course obviated.

In Figures 3 and 4, a modification of the holder is shown, and in this form the holder body 18 is shown as an elongated member, adjacent one end of which there is mounted a small pin 19. The pin 19 may be of various constructions, but preferably is of the "bar" type including a safety catch. The body 18 may be formed from any suitable light, flexible material, 10 and the bar 20 of the pin is positioned longitudinally of the body 18 and permanently secured thereto. The pin portion 21 thereof will therefore be free for insertion in the shoulder seam 15 of a garment.

The free end of the body 18 will of course be presented toward the neck of the garment, as in the first form, and placement of the shoulder strap 17 will likewise be the same.

20 In use, a smooth surface will be presented to the shoulder of the wearer, and as the safety pin will only project very slightly above the body 18, no unsightly bulge will be presented to the outer garment.

25 While I have shown and described certain preferred forms of the invention I am aware that modifications may be made, and I therefore consider as my own, all such variations in constructions as fairly fall within the scope of the appended claims.

30 I claim:—

1. A shoulder strap holding means consisting of an elongated member of sheet material having means adjacent one end but spaced from said end for securement of one end of the member 35 to a garment, the other end of said member being free but normally contacting the garment yieldingly, said free end being flexible whereby to permit placement of a shoulder strap between the garment and the free end, and whereby the 40 strap will be clasped between the member and the garment.

2. A shoulder strap holder consisting of a flat thin body member of sheet material, said body member having a transverse bar at one end, said 45 bar having a plurality of apertures for reception of securing means and the other end of the body being free but normally contacting the garment yieldingly, whereby to permit placement of a shoulder strap between the garment and the free 50 end of the body member.

EUGENE B. YOUNG.
